UNITED STATES PATENT OFFICE

146,885

DESIGN FOR A SHOE CLOG

Lester Carl Tullgren, Minneapolis, Minn., and
Joseph S. Bonkiewicz, Jr., Lodgepole, Nebr.

Application September 5, 1946, Serial No. 133,060

Term of patent 7 years

(Cl. D7—5)

To all whom it may concern:

Be it known that we, Lester Carl Tullgren and Joseph S. Bonkiewicz, Jr., citizens of the United States and residents, respectively, of Minneapolis, in the county of Hennepin and State of Minnesota, and of Lodgepole, in the county of Cheyenne and State of Nebraska, have invented a new, original, and ornamental Design for a Shoe Clog, of which the following is a specification, reference being had to the accompanying drawing, forming part thereof.

The figure is a perspective view of a shoe clog showing our new design.

We claim:

The ornamental design for a shoe clog, as shown.

LESTER CARL TULLGREN.
JOSEPH S. BONKIEWICZ, JR.
